UNITED STATES PATENT OFFICE.

JOHN R. LONG, OF AKRON, OHIO.

BENCH-VISE.

1,168,318.

Specification of Letters Patent.

Patented Jan. 18, 1916.

Application filed June 7, 1915. Serial No. 32,780.

To all whom it may concern:

Be it known that I, JOHN R. LONG, a citizen of the United States, residing at Akron, in the county of Summit and State of Ohio, have invented certain new and useful Improvements in Bench-Vises, of which the following is a specification.

This invention pertains to a double swivel bench vise constructed and adapted to operate substantially as shown and described and particularly pointed out in the claims.

In the accompanying drawings, Figure 1 is a side elevation of the complete vise and Fig. 2 is a longitudinal sectional elevation thereof. Fig. 3 is an elevation of the front or jaw end. Fig. 4 is a cross section on line 4—4, Fig. 1. Fig. 5 is a side elevation of the friction collar or belt, and Fig. 6 is an edge view thereof. Fig. 7 is a detail 20 of the yoke.

The invention herein is an improvement on the construction disclosed in my application executed April 23, 1915, and bearing Serial Number 32,101, filed June 7, 1915, and 25 the invention possesses certain differences in construction and advantages in operation over said application as will be seen in the further description herein and is clearly shown in the drawings. Thus, in the present case the so-called fixed jaw J and the movable jaw J' are operatively related, as before, the jaw J' having a tubular body, or extension 11 projected into the bore of the body 6 of the fixed jaw and slidable 35 lengthwise therein within the limits of the key-way or groove 3 and a preferably flat side plug 7 engaged in said way through the wall of the outer jaw, as before, to limit the withdrawal of the said movable jaw.

40 In the former construction I employed two supporting members or yokes for the fixed jaw, but in the present case I have a unitary or single yoke or yoke member Y but of two diameters corresponding to the 45 two diameters of the body 6 of the fixed jaw and serving as a support and bearing for the said fixed jaw, in a measure after the manner of two separate yoke members in said application but still differing therefrom in this 50 particularly,—that the present yoke, Fig. 7, is not only unitary but has a single annular or solid hub 4, which is adapted to be seated in the base B which is split at its front and adapted to be clamped tight upon 55 said hub by means of a screw or bolt. The said yoke also has a recess 5 transversely in

or across the center of its body adapted to receive the split friction clamping collar C, and which serves as a gripping or clamping medium for the tubular differential body 6 of the fixed jaw, as shown. The said collar fills the said recess 5 and extends entirely around the body of the outer jaw and is split transversely at its bottom and has threaded bosses 8 at its sides through which the 60 clamping screw 9 passes from side to side through said split, whereby the said fixed jaw can be clamped with great force and security as well as be conveniently released for rotation of the jaws when desired. It 65 follows that the yoke Y is rotatable in base B except as it is secured by clamp b and that the two jaws are rotatable together in the yoke Y except as they are clamped by collar C, the whole affording a compound swivel 70 wholly independent of each other. Both 75 clamps may be tightened or released at the same time, or one may be tight and the other loose without releasing the jaws as they may be locked on stock therein. The screw S 80 serves the usual purpose of operating the movable jaw, and the sleeve nut n in which said screw works has a collar 10 bearing against the inside of the otherwise closed end 12 of the outer jaw body while the said 85 nut n projects through said end 12 to the outside thereof and carries a friction clamping collar or cap 14 sleeved thereon and a nut 13 outside said cap to tighten the same against said end 12 and 90 to bear rotatably against the surrounding edge of the yoke. This enables the two jaws to be locked in working relation on any stock engaged therein and to be axially rotated when gripped upon said stock 95 regardless of the two swivels in the base and in collar C respectively. Of course the stock is clamped in the jaws by the screw S and this is not affected by releasing either of the two other swivels.

100 In the description and claims the word "jaw" or "jaws" is understood to include the tubular bodies thereof which are necessary portions of the said jaws or jaw members. At its front end the head 16 of screw 105 S bears against the movable jaw J' and said screw is rotatably confined in said jaw by the collar 18 thereon.

Respecting cap 14 it is to be understood that while said cap comes flush with the edge 110 of the yoke, it is not in clamping relations therewith but only with the end 12 of the

outer jaw extension, the purpose of this construction being to prevent the escape of the fixed jaw from within the yoke but to permit free rotation thereof, subject to locking 5 through the collar C. The straight bottom edge of collar C prevents the collar from rotating when clamped on the jaws and holds the jaws firmly in respect to the yoke and base.

10. What I claim is:

1. In a vise as described, a jaw supporting yoke provided with a hub on its bottom and a recess across its middle above said hub, jaws projecting through said recess and a 15 collar in said recess adapted to clamp upon said jaws.

2. A vise as described having a pair of jaws, a yoke for said jaws having a transverse recess open from above a split friction 20 collar embracing said jaws in said recess and having bosses at each side and a screw through said bosses beneath said jaws and adapted to clamp the collar thereon.

3. A vise having a double swivel as described and comprising a split base, a yoke having a hub rotatably seated in said base and adapted to be clamped therein, a pair of jaws provided with tubular bodies one within the other and extending through said 30 hub, a split collar seated in said yoke and embracing said outer jaw body, and means to clamp said collar on said body.

4. A vise having a yoke and two jaws supported therein and having tubular bodies 35 one within the other, an operating screw and a sleeve nut engaged thereby extending through the end of the outer of said bodies

and provided with a collar bearing against the inside of the end thereof, a cap over said nut outside said yoke and bearing against 40 the same and the end of said outer body and a nut to clamp said cap frictionally against said end.

5. In a vise as described, a pair of jaws, a base and a yoke therein having a recess 45 across its middle through which said jaws project and a clamp about said jaws in said recess adapted to force said parts into frictional engagement with the walls of said yoke.

6. In a vise as described, a base, a pair of jaws having tubular bodies one within the other, a yoke supporting said bodies provided with a transverse recess and a friction 55 clamp in said recess having a straight transversely split bottom portion seated in said recess and adapted to engage about said jaws and lock the same against rotation.

7. In a vise as described, a pair of jaws having tubular bodies one within the other, a supporting base and a yoke therein supporting said jaws having a transverse recess with a straight bottom transversely beneath said jaws and a split collar about said jaws fitted to the sides and bottom of said recess 60 and provided with clamping means at its bottom adapted to hold the said bodies against rotation.

In testimony whereof I affix my signature in presence of two witnesses.

JOHN R. LONG.
